UNITED STATES PATENT OFFICE.

HENRY W. WINTER, OF BOSTON, MASSACHUSETTS.

HEEL-NAILING MACHINE.

SPECIFICATION forming part of Letters Patent No. 611,370, dated September 27, 1898.

Application filed November 19, 1897. Serial No. 659,072. (No model.)

To all whom it may concern:

Be it known that I, HENRY W. WINTER, of Boston, county of Suffolk, and State of Massachusetts, have invented an Improvement in 5 Heel-Nailing Machines, of which the following description, in connection with the accompanying drawings, is a specification, like letters and figures on the drawings representing like parts.

10 This invention has for its object the production of a machine more particularly adapted, as herein shown, for the nailing of spring-heel shoes, novel means being provided for separating the nails held in bulk in a suitable 15 hopper and for transferring them to a nail-block, whence they are driven into the heel of the shoe mounted upon a suitable support.

In my present invention the nail-block and 20 the driving mechanism and coöperating support for the shoe are adapted for nailing any class of heels; but the nail-separating mechanism herein shown and described in detail is only adapted for use with nails having a 25 head or other enlargement at or near their upper ends, as will more clearly appear hereinafter.

Various novel features of my invention will 30 be fully described in the following specification and particularly pointed out in the claims.

35 Figure 1 is a front elevation of a heel-nailing machine embodying my invention, the parts being shown in position to nail a heel, although for the sake of clearness the boot or shoe is omitted. Fig. 2 is a right-hand elevation of the machine shown in Fig. 1, with one of the shoe-supports in position to have a shoe applied to it or to be removed therefrom. Fig. 3 is a vertical sectional view of the machine, taken on the irregular line x x , Fig. 1, the 40 nail-separating mechanism being omitted. Fig. 3^a is a horizontal sectional view taken on the irregular line x' x' , Fig. 3, in order to more clearly show the main driving-shaft and the connections between it and the mechanism 45 for actuating the heel-compressing mechanism, parts of the latter being shown in elevation to better illustrate the construction. Fig. 4 is an enlarged sectional view of the nail-block, with the sole-positioning device connected thereto. Fig. 4^a is an under side view 50 of the nail-block with the positioning device,

showing the mode of adjusting the latter. Fig. 5 is a rear end elevation, enlarged, of the nail-separating mechanism, said mechanism being shown in position with regard to the 55 rest of the apparatus in Figs. 1 and 2. Fig. 5^a is an enlarged view, partly broken out, of the mechanism for controlling the operation of the nailing transperrer, whereby one nail or a plurality of nails will be transferred. 60 Fig. 5^b is a longitudinal sectional view of said controlling mechanism, taken on the line x^2 x^2 , Fig. 5^a, looking toward the left. Fig. 6 is a vertical longitudinal section of the nail-separating mechanism, taken on the line x^3 65 x^3 , Fig. 5, some of the parts, however, being shown in elevation. Fig. 7 is a front elevation, on a much larger scale, of the nail-separating mechanism, with the end bearing-plate removed. Fig. 7^a is an inner side view of the 70 end bearing-plate, to be described. Fig. 7^b is a perspective view of the back bearing-plate for the nail-raceways. Fig. 8 is a longitudinal sectional view of the separating mechanism on the line x^4 x^4 , Fig. 7, looking down. 75 Fig. 9 is a transverse sectional view of a portion of the separating mechanism on the line x^5 x^5 , Fig. 8, with the nail-separators in elevation. Fig. 10 is a rear end elevation of the main 80 hopper, the auxiliary hopper being omitted, some of the shafts and a nail-raceway being shown in section. Fig. 11 is a transverse sectional view taken on the line x^6 x^6 , Fig. 8, looking toward the left. Fig. 12 is a front 85 elevation, enlarged, of the work-positioning means, the left-hand portion being shown partly in section. Fig. 13 is a top or plan view of the same with the left-hand portion partly in horizontal section. Fig. 14 is a side elevation thereof, and Figs. 15 and 16 are 90 perspective details of portions of the work-support to be described. Fig. 17 is a detached view, in front elevation, of a guide-plate attached to the fixed outer end of the main hopper, providing guideways for the 95 nails and serving to support the nail-separating and pick-off devices. Fig. 18 is a transverse sectional view thereof, taken through one of the nail-guideways. Fig. 19 is a top or plan view of the guide-plate, the upper 100 member being partially broken away. Fig. 20 is a front elevation of the bearing-plate in

which some of the rolls forming the nail-race-ways are supported; and Fig. 21 is a transverse sectional view thereof, taken through one of the nail-guideways.

5 Referring to Figs. 1, 2, and 3, the main supporting-frame of the apparatus comprises a box-like base portion A, having suitable bearings A^x for the main driving-shaft B, provided with a suitable pulley B^x, to which 10 rotation is imparted from any suitable source of power, (not shown,) the front of the base having, as shown best in Figs. 1 and 3, suitable doors A', by which ready access may be had to the interior of the base for the purpose of adjustment or otherwise.

15 The main driving-shaft B has mounted thereon a clutch B' of any suitable construction, the loose member of which has an attached gear B², the said clutch being controlled by a detent B³, fast on a rock-shaft B⁴, mounted in the base of the frame and operated by a suitable treadle B⁵, (see Figs. 1 and 2,) the withdrawal of the detent permitting the clutch to operate, whereby the gear B² 20 will be rotated by and in unison with the main driving-shaft. This gear is in mesh with the toothed periphery of a cam C, fast on a shaft C', mounted in suitable bearings in the base, said cam having in one side 25 thereof (see Fig. 3^a and dotted lines, Fig. 3) a cam-groove c³⁰⁰ to act upon a suitable roller or other stud 3 on the detent to hold the latter inoperative for one complete revolution of the clutch-gear after the latter has been 30 started by the operator, so that the operation of the machine will not be stopped prematurely should the operative remove the pressure from the treadle. This construction is well known in apparatus of this and similar 35 character wherein the operator starts the apparatus at will and stoppage is automatically effected at the proper time.

40 The cam-shaft C' has fast thereon two outer cams C² C³, the outer cams C² C³ being alike and having in their outer faces like grooves c² c³, respectively, to be entered by suitable roller or other studs c⁴ c⁶ (see Fig. 3^a) on like 45 links D, longitudinally slotted at d to straddle the cam-shaft C', the outer ends of the 50 links being pivotally connected to one of the arms D' of a pair of toggles located, respectively, near the sides of and at the front of the base, the upper end of each arm D' having a lateral hub d', supported in suitable 55 bosses A³ (see Fig. 3^a) of the base and also forming bearings for a shaft E to be described.

60 The toggle-arms D² are pivotally connected at their lower ends to studs on collars d², fast on vertical plungers D³, mounted in and 65 guided by the base of the frame A, said plungers having bearings for their lower ends in hollow bosses A⁴ within the base. (See dotted lines, Figs. 1 and 3.) The plungers extend upwardly above the frame for some distance and have at their upper ends a connecting cross-head D⁴, rigidly attached thereto.

As shown in Figs. 1, 2, and 3, the frame is

upwardly extended to form an overhanging head A⁵, laterally extended at A⁶ to provide vertical guides or bearings A⁷ for the plungers D³ below the cross-head. The cross-head has suitably attached thereto a gang of drivers D^x for the nails, the gang of drivers being attached in any suitable manner to the cross-head, which latter has at the rear of its center a vertical opening d⁸ and two larger openings d⁹ (see dotted lines, Fig. 1) for a purpose to be described.

70 The part A⁶ of the overhanging head of the frame is recessed from its front face to receive the nail-block, (shown in section in Fig. 4,) said nail-block being built up of superposed plates of metal a, with vertical registering openings a' therethrough to form nail-passages, two of the sections, as best shown 75 in Fig. 1, extending laterally beyond the others to form guides which slide into the correspondingly-grooved sides of the recess in the part A⁶ of the head to position the nail-block in place.

80 The main object in making the nail-block in section, as described, is to enable suitable nail-detents a² to be inserted, said detents being made, preferably, of spring metal projecting into the nail-passages a' at one side 85 and held in place by screws or other suitable means a⁸, said detents being located at the outermost sides of the passages to act in guiding the nails inward toward the center of the heel as they are driven.

85 The top plate a⁴ of the nail-block is shown as having a raised wall a⁵, substantially corresponding in shape to the shape of the heel, with holes a⁶ therein forming upper continuations of the nail-passages a', and inclined throats a⁷ leading into said continuations a⁸ to convey the nails thereto from the nail-transferring mechanism to be described, it being understood that the nail-drivers D^x reciprocate vertically in the passages a' a⁶, 90 while the detents a² prevent in usual manner discharge of the nails from the bottom of the block until positively driven therefrom by the drivers.

95 The raised wall a⁵ of the top plate or section a⁴ of the nail-block is cut away at the upper ends of the nail-driving holes or passages a⁶ to thereby decrease the distance from the top to the bottom of said nail-driving passages as a whole, enabling the use of much 100 shorter drivers. This is a decided advantage, because the longer the driver the greater the liability thereof to buckle or bend in driving the nail, and any material reduction in the length of the driver will obviate such 105 buckling tendency.

110 Referring to Fig. 4, it will be seen that by cutting away the wall above the driver-passages the upper or outer ends of the delivery-throats a⁷ will be located above such cut-away portion to permit free access of the nail-conducting tubes or passages to the upper ends of the throats.

115 The nail-block forms a support for the heel

of the boot or shoe, the latter being subjected to a predetermined fixed pressure, as will be hereinafter described.

The horizontal portion A⁸ of the frame, located below the overhanging head and part A⁶ thereof, forms a bed and is provided, as herein shown, with lateral guideways a⁸ for a laterally-movable carriage b^x, (see Fig. 16,) said carriage having vertical openings 6 and 8 therein and being grooved longitudinally at its front and rear edges at b' to engage the guides a⁸ referred to, said carriage having at its opposite ends overhanging lips or flanges b², which form in turn guides for a slide-block F, (see Fig. 15,) having a flat extended base with overturned ends f to embrace the guide-flanges b², the block F also having vertical openings f⁶ and f⁸ to at times register with the openings 6 and 8 of the supporting-carriage b^x, the latter being elongated, as shown in Fig. 16, for a purpose to be described.

The carriage b^x is provided, as shown in Figs. 2 and 3, with an upturned lug b³, in which is mounted an adjusting-screw b⁴, taking into a threaded opening 80 (see Fig. 15) in the slide-block to adjust the latter toward the front or rear of the carriage b^x in order to properly adjust the work with relation to the nail-blocks, as will fully appear. The said slide-block is shown as vertically elongated to receive and form bearings for two short slide-rods f', which extend down into the openings 6 and 8 of the carriage and which have fast on their lower ends collars f², against each of which bears one end of a strong spring S, (see Fig. 3,) the other end of the spring bearing against the top of the elongated portion of the block, the spring normally tending to maintain the rods f' in the position shown in Fig. 3, with the collars resting on the bed-plate, and preferably the lower end of each rod is slightly beveled or rounded at its edges, so that in the lateral movement of the carriage b^x, taking with it the block F, said rods will be perfectly free to move over the bed-plate.

The upper ends of the rod f' have pivoted thereon each a shoe-holder (shown as an arm f³) of suitable length and provided with a head f⁴, having a hardened-steel face f⁵ to clench the nails as they are driven from the nail-block into the heel, the shoe-holders being pivoted at 9 to swing outward toward the operator to enable him to place a shoe thereupon or to remove one from it.

Referring now to Figs. 1 and 3, the bed A⁸ of the frame has, as herein shown, three depending like bosses 10 12 14 to guide, respectively, like vertically-movable plungers 20 22 24, each plunger having an enlarged or annularly-flanged head to support the lower end of a spring S^x, surrounding the corresponding boss and between the under side of the bed A⁸ and the flange on the plunger, each of said plungers having a longitudinal slot 15 therein (see Fig. 3) to be entered by a suitable stud 16 in the boss to prevent rotation of the plun-

ger. The upper ends of the plungers are normally substantially flush with the upper face of the bed, and each plunger carries at its lower end, preferably, a roll 18, which rests upon a suitable cam E^x, three of said cams being shown in dotted lines, Fig. 1, and in plan, Fig. 3^a, loosely mounted on the shaft E, hereinbefore referred to, the shape of the cams, which are all alike, being shown best in Fig. 3. Each cam is provided with a carrier, shown as comprising two disks e^x, keyed to or otherwise movable with the shaft E and having interposed washers w, of leather or other suitable material, between them and the cam, said disks e^x, washers, and the cams being connected to move together frictionally by means of suitable bolts e', passed through the cam and disks e^x, forming the carrier, the cam having elongated slots e², (see dotted lines, Fig. 3,) through which the bolts pass.

It will be obvious from the foregoing that if the cam-carrier is rotated the cam will rotate therewith in unison until the friction between the cam and its carrier is overcome, whereupon the movement of the carrier may continue after the stoppage of movement of the cam.

One of the disks of the center cam-carrier, as herein shown, is toothed for a portion of its periphery at e³ to form a segmental gear in mesh with a rack-bar e⁴, mounted to slide in a horizontal bearing A⁹ of the base of the frame and connected at its inner end with an actuating-link C⁵, slotted to embrace the cam-shaft C' and carrying a suitable roller or other stud c¹⁰ to enter a cam-groove C⁶ (see Fig. 3) in one face of the cam C, heretofore described. The shape of the groove C⁶ is such that movement will be imparted to the rack-bar e⁴ to partially rotate the cam-carriers on the shaft E, the beginning of the movement being rapid, and thereafter, while the nailing is being effected, the movement of the carriers ceases, and after the nailing is completed the carriers are moved in a reverse direction to restore the parts to starting position.

The acting periphery of each of the cams E^x comprises a dwell portion from 1 to 2, Fig. 3, then a quick rise from 2 to 23, and from the latter point a gradually-increasing rise, so that when the cam-carriers are moved in the direction of the arrow 50, Fig. 3, the plungers 20, 22, and 24 will be quickly raised when their rolls 18 are engaged by the quick rise of the cam, and thereafter, the cam continuing its movement, the rise of the plungers will be more gradual.

The plungers are so located that the center one and either of the outside ones may be made to act upon the slide-rods f', mounted in the carriage b^x, to elevate said slide-rods and compress the heel and adjacent portion of a sole of the shoe on the corresponding shoe-holder f³ in position to have the heel thereof nailed and to simultaneously spank the heel of a shoe mounted on the other holder.

If the parts are in the position shown in

Fig. 1, the operator will place a shoe on the right-hand shoe-holder f^3 , which is then located above the center plunger 22, and, swinging the shoe-holder in, will start the machine. 5 The center cam E^x will then operate upon its plunger 22, raising the same and with it the shoe upon the holder until the bottom of the heel is brought to bear upon the heel-support—viz., the under side of the nail-block—10 and the heel will be subjected to compression between the heel-support and the shoe-holder, the amount of pressure to which the shoe is to be subjected being predetermined and regulated by the amount of friction between 15 the cam E^x and its carrier.

Inasmuch as the height and density of heels vary quite considerably even with stock substantially uniform, it is highly desirable to subject each heel to no more or no less than 20 the predetermined amount of pressure, and in my present invention I have made the height and density of the heel effective to control and automatically render the compressing mechanism inactive after the predetermined pressure has been obtained. 25

The "pressure-cam" E^x , as it may be termed, will continue to move with its carrier, and thereby impart a gradually-increasing pressure to the heel until the predetermined 30 pressure has been attained, and at such point the resistance offered by the compression of the heel to the continued rotation of the cam will be sufficient to overcome the friction between the cam and its carrier, and there will 35 be slip or lost motion between them, the cam remaining stationary while the carrier completes its throw. Upon the return movement of the carrier the cam will be positively returned to starting position, as the ends of the 40 slots in the cam will be engaged by the bolts e' until the projecting portions e^6 of the cams are engaged by a fixed stop, shown as a bar e^1 , extended across and fixedly mounted in the frame, and when the stop acts the return 45 movement of the cam is stopped, while the slight further movement of the carrier restores the parts to their relative position. (Shown in Fig. 3.) The operative then moves the carriage, and thereby the shoe-holders, to 50 the right, viewing Fig. 1, until the left-hand holder f^3 of the pair is brought into position to have the heel of the shoe, now placed thereon, compressed at the next operation of the machine, such movement of the carriage being 55 readily effected by means of a hand-lever 75, pivoted on the main frame at 76 and provided with a stud 77, which enters a vertical groove f^7 in the block F on the carriage.

By swinging the handle 75 from left to 60 right the carriage is moved to the right and the rods f' of the two work-holders are brought into position above the plungers 22 and 24. In this position the work on the holder above the center plunger is in position to have the 65 heel compressed and the nails driven thereinto, it being understood that while the heel is compressed, as has been heretofore described,

the toggles are straightened by means of the cams C^2 C^3 to depress the cross-head D^4 and lower the drivers D^x to drive the nails from 7 the nail-block into the heel. Now when the apparatus is again started to operate upon the second shoe the plunger 24 will raise the shoe-holder, having thereon the shoe, the heel of which has been nailed, and such heel is 7: raised against the part 25 of the under side of the overhanging head, the two parts 25 being located at opposite sides of the nail-block and serving as spanker-plates to either level the bottom of the nailed heel or, if the nails have 8: been left slightly projecting, to spank a top lift upon the same.

When the heel of the second shoe has been compressed and nailed, the operator removes the shoe first operated upon and places the 8 third shoe upon the right-hand holder, (shown in Fig. 1,) it being remembered, however, that the holders are shifted to the right-hand side of the bed. The carriage is then shifted back into the position shown in Fig. 1, and the 9 third shoe is then in position to have its heel compressed and nailed, while the second shoe, previously nailed, is spanked as described.

It is necessary to position the boot or shoe upon the holder during the heel compressing 9 and nailing operation, and particularly in spring-heel shoes, wherein the heel end of the sole, with its attached wedge, which, with the sole, forms the heel, is not nailed to the heel end of the shoe when the latter is operated 10 upon in the nailing-machine.

Heretofore, so far as I am aware, it has been usual or necessary to position the heel end of the sole relatively to the shoe by inserting one or more nails before the work is operated 11 upon by a regular nailing-machine. In my present invention, however, I have provided work-positioning devices which serve to position the heel end of the sole and attached wedge in a spring-heel shoe and also to center and accurately position the heel upon the shoe while being compressed and nailed, so that no preliminary fastening is necessary.

On the under side of the nail-block (see Fig. 4^a) I mount two preferably adjustable gages g , the downturned portions of which embrace the sides of the sole and the heel-forming wedge when the shoe-holder f^3 is in proper vertical position, and by means of the slots g' in the gages I am enabled to adjust 1 them to accommodate soles of different widths, the gages being held on the nail-block and in adjusted position by suitable screws g^2 . Below the overhanging head the upwardly-extended portion of the frame is provided with 1 a transverse preferably undercut groove g^3 , Figs. 1 and 3, to receive a slide-plate g^4 , (shown in side elevation on a larger scale in Fig. 14 and in plan view in Fig. 13,) said slide-plate having two sets of vertical guideways g^5 , to receive each a vertically-movable stand g^6 , said stands being connected by flat springs s with the upper ends of two slide-rods f' , so that when the latter are moved vertically the

said stands will be moved by and in unison with them. These stands are recessed interiorly to receive each a substantially L-shaped support g^7 , the horizontal foot of said supports sliding in and out on guides g^8 in the stands g^6 . Each of these supports g^7 is provided with raceways to receive antifriction-balls g^9 , (see dotted lines, Fig. 12,) on which travel the laterally-extended and overlapping bases $h^x k^x$ of outwardly-extended and upturned arms $h k$. (Shown clearly in Figs. 12, 13, and 14.) The base h^x is shown in Fig. 13 as recessed to receive the base k^x of the other arm, the bases being provided with rack-teeth $h' k'$, respectively, in mesh with a pinion g^{10} , fast on a shaft g^{12} , mounted to rotate vertically in the support g^7 , the arms being connected by a spring S^2 to normally draw them together, as shown in the drawings. At the outer upturned ends of the arms I have fulcrumed levers $h^2 k^2$, shaped at their outer ends to form clamping members $h^3 k^3$, which bear against and grasp the counter of the shoe adjacent to and below the heel when the work is on the holder. The inner ends of the arms are connected by links $h^4 k^4$ to a disk or head g^{13} , rotatably mounted on a cap-plate g^{14} , rigidly secured to the stand g^6 and provided on its under face with suitable raceways for antifriction-balls g^{15} (see dotted lines, Fig. 12) for the upper edges of the arm-bases $h^x k^x$.

A back gage g^{16} for the back of the counter of the shoe is adjustably mounted on the cap-plate and is held in adjusted position by a suitable set-screw g^{17} , Figs. 13 and 14, the back gage being adjusted in or out, according to the length of the heel or the size of the shoe to be operated upon.

When the shoe-holder f^3 is moved back into vertical position, the heel end of the sole enters between and is positioned by the gages g and the counter of the shoe is embraced by the clamping members $h^3 k^3$, the spring S^2 permitting the arms which support said members to separate sufficiently to permit the entrance of the counter, and by virtue of the rack-and-pinion connection between the laterally-extended bases of said arms the latter move an equal distance away from the center, to thus insure the accurate positioning of the shoe relative to the heel, which is positioned, as has been stated, by the gages g on the under side of the nail-block. The pivoted arms $h^2 k^2$ rock laterally to accommodate the clamping members to the shoe, and this rocking movement is equalized by means of the links and rotatable disks g^{18} . Each of the outer upturned arms k^x is provided with a lug carrying a stop-screw 27, which limits the inward movement of each pair of arms toward each other due to the action of the spring S^2 , the stops being set according to the width of the shoe to be nailed. Now when the operative moves the carriage b^x laterally on the bed of the frame, as has been

described, the stand g^6 and slide-bar g^4 will be moved laterally in unison therewith, and when the compression mechanism operates to elevate the slide-rods f' , carrying the work-holders, the stands g^6 will slide vertically on the slide-bar g^4 , thus maintaining the shoe-positioning device in the same position relative to the shoe-holder when the latter is moved laterally. By means of the ball-bearings for the arms h and k the movement thereof is made very easy and wear is reduced to the lowest possible limit.

In Fig. 12 I have shown at 28 the guideway for the back gage g^{16} . The balls g^9 and g^{15} are retained in place by suitable pins 30 and 31.

Referring to Figs. 1 and 3, the top member a^5 of the nail-block has secured thereto two brackets a^{12} , which are located at the outside of the nail-passages and which support the upper ends of a series of nail-transmitting tubes a^{13} , the lower ends of said transmitting-tubes being connected in any suitable manner with the delivery-throats a^7 , said tubes being conveniently formed of spiral springs and in themselves forming no part of my invention. The connection of these transmitting-tubes with the nail-block enables me to remove the nail-block and tubes bodily when desired in changing from a large to a small size shoe, or vice versa.

The nail-separating mechanism as a whole comprises a hopper to receive nails in bulk, and means to take the nails from the hopper onto the raceway, along which they travel to a transerrer, which latter is so constructed that one nail or a plurality of nails may be transferred to a receiver, the nails being distributed from the receiver to the nail-transmitting tubes mounted on the nail-block.

The upturned portion A^5 of the main frame has at the rear of the nailing mechanism a horizontal bearing A^{12} (see Fig. 3) for a turn-table M , having upturned ears m , on which is pivoted a frame M^x (see Fig. 2) of the nail-separating mechanism now to be described, said separating mechanism being adapted to be tipped on a horizontal fulcrum m' and to be swung laterally on the bearing A^{12} , said frame M^x having a depending bearing M' concentric with the center of rotation of the turn-table and resting upon a suitable track A^{13} on the main frame of the machine, to thereby enable the separating mechanism to be swung horizontally, when desired, to one side. The turn-table is retained upon its bearing by means of an undercutting m^x , secured in any suitable manner to the main frame, as by screws 32.

The frame M^x is provided with a vertical bearing m^2 (see Fig. 6) for an auxiliary shaft N , having thereon, above the bearing, a worm n and a beveled gear n' and feathered or splined thereon, below the bearing, a second and larger beveled gear n^2 , said shaft being concentric with the vertical fulcrum, about which the nail-separating mechanism can be

swung laterally, said gear n^2 being normally held in operative position by a check-nut n^{200} on a threaded part of the shaft N. (See Fig. 6.)

A main or actuating shaft N^x (see Figs. 2, 5 3, and 6) is mounted in suitable bearings 33 34 in the main frame and extends up through the center of the turn-table M and is connected with the lower end of the auxiliary shaft N by any suitable universal joint N' , 10 so that the actuating and auxiliary shafts need not be disconnected when the nail-separating mechanism is tipped on the turn-table, it being noticed that the joint between said shafts is in line with the horizontal ful- 15 crum m' for this purpose.

The lower end of the actuating-shaft N^x is provided, preferably, with a friction-disk n^3 , Fig. 3, driven by a second friction-disk n^4 , fast on a shaft n^5 , mounted in the main-frame 20 base and driven by a suitable belt B^8 (see dotted lines, Fig. 2) from the main driving-shaft. I prefer to use friction-disks in this instance rather than gearing, so that there will be no breakage of any of the parts of the 25 nail-separating mechanism should free movement of the same be impeded.

The frame M^x supports, as herein shown, main and auxiliary hoppers H and H' , the hopper H comprising a rotatable body portion 30 having annular raceways $h^{15} h^{16}$, Fig. 6, for antifriction-balls 40 and 42, respectively, the series of balls 40 being held in place by one of the fixed ends H^2 of the hopper, while the series of balls 42 are held in place by the 35 other end H^x of said hopper, the latter also forming one of the ends of the auxiliary hopper H' . The fixed hopper end H^2 is rigidly secured to the frame M^x , and the two ends $H^2 H^x$ are rigidly connected by suitable bolts 40 43, (see Fig. 7,) the said bolts being extended through sleeves which separate the hopper ends and prevent their being drawn too tightly together, one of such sleeves h^{17} being shown in Fig. 6.

The hopper-bodies H H' are shown as connected by a suitable brace 45 to rotate in unison, the body H' being provided with or having formed thereon a spur-gear h^{18} , in mesh with a pinion h^{19} , fast on a shaft h^{20} , said shaft 50 at its other end being provided with a beveled gear h^{21} , in mesh with the gear n^2 on the auxiliary shaft and from which it is driven to rotate the hopper-bodies. By loosening the check-nut n^{200} the gear n^2 can be lowered out 55 of engagement with the gear h^{21} , so that the body portion of the hopper can be reversely rotated by hand to quickly empty the nail-lifting devices. The shaft h^{20} is mounted in a bearing m^8 , forming a part of the end plate H^3 of the auxiliary hopper, said plate being 60 bolted or otherwise secured to the frame M^x .

The hopper-body H' is mounted to rotate on antifriction-balls 46 and 48, (see Fig. 6,) which travel in raceways in the end plate H^3 65 and intermediate plate or hopper end H^x . The intermediate plate H^x (shown on an enlarged scale in Fig. 10) has an annular pro-

jection h^{22} , which serves as a guide for the part h^{23} of the auxiliary hopper-body H' , the part h^{23} being substantially an annular in- 70 turned flange providing the raceway for the series of balls 48. The rib or flange h^{22} also acts to cover the joint between the intermediate plate H^x and the adjacent part of the hopper-body to absolutely prevent the entrance of any nails or nail-points. By referring to Fig. 6 it will also be seen that the other side of the auxiliary hopper-body is let into the end plate H^3 for the same purpose. The annular joints in the main hopper between 75 the body and fixed ends thereof are also protected in like manner, so that it is impossible for the hoppers to become jammed by entrance of the nail-points into the joints.

The body portion of each hopper is pro- 80 vided at its interior with nail-lifting devices, which act to lift the nails from the bulk of nails and to discharge them onto the raceway, the latter, as will be described, being arranged in a single plane across the hopper, 85 and in order to discharge the nails as equally as may be upon all of the raceways the lifting devices are of peculiar and novel construction.

Referring to Fig. 7, the lifting devices are 90 shown as shelves 60, secured to the inner surface of the hopper-body and of different lengths and inclinations, (see dotted lines,) the longer shelves, one of which is shown at the highest point in said figure, making deeper 95 pockets and retaining the nails therein until the rotation of the hopper-body has carried the shelf far enough over to discharge the nails, the main discharge of the nails from such deep pockets taking place at the far 100 side of the hopper and properly maintaining the farthest raceway supplied with nails. The shallower pockets discharge their nails sooner, and the inclination of the shelves also varies the time at which the nails will 105 be discharged, so that a full supply of nails will be provided for all of the raceways, those farthest from as well as those nearest to the higher or lifting side of the hopper-body.

Referring to Figs. 6, 8, 17, 18, and 19, a 110 guide-plate O is secured to the hopper end H^2 , said guide-plate being preferably formed in two parts for convenience, the under member having a series of vertical slots o, extended from front to back of the plate, and after 115 the two members of the plate are secured together holes o' are bored therethrough adjacent the upper ends and opening into said slots, as shown in Fig. 17, to receive the outer ends of rolls R R' , arranged in pairs and 120 forming raceways along which the nails travel to the lower ends thereof, said raceways being shown as inclined to the horizontal 125 in Fig. 6. The rolls simply pass through the guide-plate O, but they do not take their bearings therein, as the said rolls are supported in end bearings, some of which are shown in section in Fig. 8.

The guide-plate O is outwardly extended

to form a support for a bearing-plate P, (shown separately in Figs. 20 and 21 and in section in Fig. 8,) said plate having cut-away portions p to receive the ends of the rolls R R', and, as shown in Fig. 8, the rolls R are longer than the rolls R', the end of each roll, however, having a raceway, as r^x , Fig. 9, to receive suitable antifriction-balls 80, held in place by an end-thrust bearing, shown as a plug p' let into the bearing-plate P in alinement with the ends of the rolls R.

In Fig. 8 I have shown four main raceways—that is to say, raceways which receive their nails from the main hopper H. The shorter rolls R' are also provided at their outer ends with ball-raceways, one being shown in section in Fig. 8 to coöperate with the pick-off, shown as a spirally-threaded roll R^x , having at its outer end a ball-bearing held in place by an end-thrust bearing-stud r , each raceway having such a pick-off at its delivery end, the bearing-studs r being supported in an end plate Q, suitably bolted to side plates Q', which in turn are attached, as by screws Q ^{2} , to the guide-plate O. The inner end of the thread runs down to a point, as r' , Fig. 8, and the adjacent roll R of the raceway extends beyond the path of the point of the pick-off, so that in the rotation of the pick-off the nail will be maintained in motion by the rotation of the roll R.

From the foregoing description it will be obvious that the nails are discharged from the hopper-pockets onto the raceway, and the bodies of the nails depend from between each pair of rolls forming each raceway, said rolls being rotated in opposite directions away from each other, tending to continually lift the nails, the heads or other enlargement at or near the upper ends of the nails preventing them from dropping through between the rolls.

The rotation of the rolls, together with their inclination, causes the nails to travel down to the lower end, and they are there engaged one by one by the pointed end r' of the pick-off and carried along to a point from which they are delivered, as will be described.

Each of the pick-offs is provided at its outermost end with a gear r^2 , and said gears are connected in pairs by intermediate pinions r^3 , (see Fig. 7^a), mounted in the end plate Q, rotation being transmitted to said series of pick-offs by means of a gear r^4 , fast on a shaft r^5 , driven by suitable means to be described.

In Fig. 7^a one of the end-thrust bearing-blocks r , with its ball-raceway 81, is shown in end elevation. As the nails pass down the raceway their depending body portions travel through the guideways o of the guide-plates O and also through guideways in the bearing-plate P described, so that the passage of a nail through said plates is free and unobstructed, the continuous top member of the plate O preventing the nails from jumping up and out of the raceways as they pass therethrough. To prevent any such action while

the nails are passing through the bearing-plate P, I provide a cover-plate P', (see Fig. 9,) which is supported by and on the top of the bearing-plate, said cover-plate having downturned fins or ribs p^2 , which enter the upper portions of the nail-passages in the bearing-plate. The upper ends of the rolls R R' are provided with meshing gears 83 84,

respectively, the rolls passing through the transversely-extended and set-in part H¹⁰ (see Fig. 11) of the division-plate or end wall H^x between the main and the auxiliary hoppers, said portion H¹⁰ being recessed to receive the intermeshing pair of gears 83 and 84. On the concaved side of the end wall H^x and adjacent the part H¹⁰ is secured a transverse bearing-plate H¹², through which the rolls R freely extend and in which are mounted end-thrust

bearings for the rolls R', shown best in Fig. 8 as threaded studs 86, screwed into place and having raceways for suitable antifriction-balls between their inner ends and the adjacent ends of the raceway-rolls R'. The rolls R after passing through the bearing-plate H¹² are provided with gears 85 and with end raceways for ball-bearings, which are held in place by threaded studs 87, mounted in a transverse bearing-plate H¹³. (Shown separately in Fig. 7^b, the inner face of the plate being shown in said figure.) The plate H¹³ also supports intermediate gears 88, in mesh with the gears 85 of the two rolls R at each side of the hopper, said gears 88 being preferably mounted in ball-bearings, as shown in section, Fig. 8, the adjustable cap member 89 of the bearing for the gear being shown as a stud adjustably mounted in the plate H¹³.

The pair of gears 85 nearest the center of the hopper (see Fig. 10) are in mesh with a large gear 90, shown as a peripherally-toothed ring having ball-raceways at its faces, one of said balls being held in place by the plate H¹³, while the other series is held in place by an auxiliary or retaining plate 91, secured by suitable screws 92 to the hub-like portion H¹⁴ of the plate H¹³. The large ring-gear 90 is driven by a pinion 93, fast on a shaft 94, having end-thrust bearings, one of which is in

the plate H^x and the other in a bracket H¹⁵, secured to the hopper end H³, said shaft 94 having a beveled gear 95 thereon, in mesh with the pinion n' and the auxiliary shaft N, heretofore described.

From the foregoing description it will be seen that by means of the auxiliary shaft N and transmitting-shaft 94 the rolls R of each pair of rolls comprising a raceway are rotated positively, and by means of the meshing gears 83 84 of each pair of rolls, the rolls R' of each raceway are rotated in the proper direction, and by providing end-thrust ball-bearings for the rolls, as described, I reduce the friction to a minimum and absolutely obviate the use of oil or any other lubricating material.

Referring now to Figs. 6, 9, and 18, the guide-plate O is shown as extended toward

the front or delivery end of the nail-separating mechanism to provide supports for two longitudinally-movable slide-plates $s^6 t^5$, extended across and below the lower ends of 5 the raceways, each of the plates having upturned pointed or beveled fingers $s^6 t^6$, which are adjacent each other and at times close to the path of the points r' of the pick-offs, and the movements of the plates $s^6 t^5$ are so timed, 10 as will be described, that first the finger t^6 is moved across the passage between the rolls comprising the raceways to engage the body of the endmost nail of the series of nails in the raceway and thereby maintain said nails 15 in upright position, and then the plate s^6 is moved to move the fingers s^6 between the bodies of the endmost nail and the nail next above it to separate such endmost nail from the series and permit the point of the pick- 20 off to enter between the endmost nail and the next one just below their heads to move the endmost nail from the raceway into the spiral groove on the pick-off. As the point r' of the pick-off engages the endmost nail the detent- 25 finger t^6 is withdrawn from in front of said nail, so that the latter is free to be moved along as it travels in the spiral groove, and at such time the separator-finger s^6 remains in position, holding the series of nails until 30 the detent t^6 has again moved into operative position, whereupon the separator moves back and lets the series of nails move down to the detent, and then the separator s^6 again comes forward to separate the endmost nail.

35 Referring to Fig. 9, the guide-plate O is shown as recessed to receive a suitable spring t^7 , the free end of which is attached to a pin extended down from the plate t^5 through a slot 100 in the plate O , and a similar spring 40 s^7 (see Fig. 6) is connected with the plate s^5 . The tendency of these springs is to normally move said plates to the right to bring the separator and detents into operative position, and the movement of the plates in the re- 45 verse direction is effected by cams $s^8 t^8$, bearing against shoulders on the two plates at the proper time, said cams being mounted on a shaft r^5 , the detent and separators being positively withdrawn from and yieldingly 50 moved toward the nails, for the reason that should the point of a separator or detent engage a nail the mechanism will not be injured, the spring permitting sufficient yield. The spirally-grooved rolls R^X constitute intermittently-movable transferrers to transfer one or more nails from each raceway to a receiver, from which latter the nails are distributed by suitable tubes or passages to the nail-block, and coöperating with each transferrer 55 60 is a retaining device to prevent discharge of the nail or nails from the transferrer until the operative movement of the latter has been completed.

It will be understood that at each rotation 65 of the transferrer the pick-off r' will pick one nail from the raceway, and consequently if more than one nail is to be transferred from

each raceway the transferrer will be rotated as many times as the number of nails to be transferred before the retaining device will 7 be moved to permit the nails to be discharged into the receiver.

The space between the end plate Q , sides Q' , and the bottom of the guide-plate O is filled in by two slide-plates S^5 and T^5 , which 7 are mounted to slide on ball-bearings in the end plate Q and guide-plate O , while a series of balls 102 (see Fig. 6) is interposed between the adjacent longitudinal edges of said slide-plates, one of the plates, as S^5 , having mounted thereon a series of retaining devices, shown as upturned ledges S^6 , which are at times 8 closely adjacent the transferrer R^X , to form a continuous support for the nail-heads as they travel along in the spiral groove of the 8 transferrer after they have been picked off from the raceway.

The plate T^5 has erected upon it a series of upright walls T^6 in parallelism with the ledges S^6 and movable toward and from the latter, as 9 will be described, the faces of said walls toward the ledges being vertically grooved to form a series of open-ended pockets T^7 , corresponding in number to the greatest number of nails which can be discharged at any one time from the transferrer and corresponding, as a matter of course, with the number of openings made by the spiral groove of the transferrer with the retaining-ledge S^6 when the latter is in operative position, the transferrer always 1 stopping its rotation in the position shown in Fig. 8.

The plate T^5 has holes therein registering with such of the pockets T^7 as are located above such plate, and for the remaining 1 pockets, which extend over the plate S^5 , the latter has holes S^7 , with which the pockets will register when the parts are in the position shown in Fig. 7. The plate S^5 is acted upon by a spring S^8 (see Figs. 7 and 8) to move the retaining-ledges S^6 in a yielding manner toward the transferrer, and the plate T^5 is acted upon by a spring T^8 to move the walls containing the nail-pockets yieldingly toward the retaining devices, while a suitable stop-screw 104 limits the return movement of both plates to the left, viewing Fig. 7, inasmuch as said screw stops the plate S^5 , and the ledges S^6 thereon stop the walls T^6 on the plate T^5 . The rock-shaft t^8 is extended through the hopper and at its front end is connected by a suitable arm t^9 with a lug t^{10} on the plate T^5 to move the latter in a direction opposed to the spring T^8 to move the receiving-pockets T^7 to the right, Fig. 7, and away from the upturned ledges S^6 , it being obvious that as the pockets are thus moved the slide-plate S^5 will follow, owing to the spring S^8 , until the retaining-walls S^6 are stopped by engagement with the transferrers, and then the pocket portions 1 continue to move a little farther to sufficiently open up the space between the walls T^6 and ledges S^6 , so that the nail or nails moved along by the transferrer may have a

free passage. When the transferrer has completed the desired number of rotations to transfer a corresponding number of nails into position to be discharged, the rock-shaft is moved in the opposite direction, as will be described, and the spring T^8 moves the plate T^6 to the left, Fig. 7, until the pockets are enclosed on their upper side by the ledges S^6 and the latter moved into discharging position (shown in Fig. 7) to permit the nails to drop down from between the transferrers and retaining-ledges into the pockets and into suitable distributing-tubes leading therefrom. The spring T^8 is stronger than the spring S^8 to effect the latter movement.

The tops of the ledges S^6 are beveled or inclined on their inner corners to facilitate the discharge of the nails.

A bracket 106, secured to the overhanging head of the main frame of the apparatus, has an overturned shelf-like portion 107, (see Fig. 3,) which extends directly beneath the lower ends of the pockets of the receiver when the nail-separating mechanism is in normal position, said shelf having openings therein to register with the open ends of the pockets and supporting the upper ends of the flexible nail-distributing tubes t^8 , Fig. 1, said tubes being led through the openings d^8 and d^4 in the cross-head down to a frame 108, registering with the upper ends of the nail-transmitting tubes a^{13} .

When it is desired to swing the nail-separating mechanism to one side on its turntable, the nail-distributing tubes will not be disturbed and will be in proper position when the separating mechanism is swung back into operative position again.

As shown in Fig. 2, the hoppers are provided with suitable removable doors 112 114, by which nails may be inserted into or removed from the hoppers.

The auxiliary hopper is provided with a single raceway, as herein shown composed of two rolls R^5 R^6 and extended through the main hopper, and in their construction and mounting being substantially duplicates of the raceway-rolls hereinbefore described, with the exception that the roll R^5 has one of its end-thrust bearings as a stud 115, mounted in a bracket H^{16} , secured to the hopper end H^3 , said roll having a gear 55 meshing with a gear 56 on the roll R^6 , and also having outside of the hopper end H^3 a gear 57 in mesh with a gear 58 on the shaft 94, hereinbefore described, and from which the said raceway-rolls R^5 R^6 are driven.

It will be obvious that the pick-off separating and transferring mechanism for the nails traveling along the raceway from the auxiliary hopper forms a part of the main mechanism for performing such functions.

To facilitate clearing the raceways of nails by tilting the hopper, I have shown each raceway-roll at its upper end as reduced in diameter at 120, Fig. 8, to enlarge the space between the rolls, so that by tipping the hopper

up upon its fulcrum m' the raceway can be cleared, although the machine may be in operation.

By providing an auxiliary hopper I am enabled to use nails of two different lengths at the same time, the nails of one length being held in bulk in the main hopper and those of another length in the auxiliary hopper, and in order to prevent the nails from the main hopper from entering the auxiliary raceway I place a guard G^{10} (see Fig. 6) above the part of the auxiliary raceway passing through the main hopper, as shown in Fig. 6, said guard having inclined sides, which shed the nails from the main hopper off of the raceway. As shown in dotted lines, Fig. 10, I may also place inclined directing-plates G^{12} in the main hopper between and above the main raceways to assist in directing the nails down into said raceways.

The part H^{10} and the retaining member 91 for the ring-gear 90 are apertured for the passage therethrough of the rolls R^5 and R^6 , as is also the plate H^{12} , and a vertical slot is made in said fixed parts of the apparatus, as shown in Figs. 6, 7^b, and 11, for the passage of the nail-bodies as they travel down the auxiliary raceway.

To remove any surplus nails from the raceways, I may employ brushes, as B^{20} B^{22} , five of the former brushes being shown in dotted lines, Fig. 7, arranged above the auxiliary and main raceways and mounted in a bearing-plate B^{28} in the hopper end H^3 , said brushes being mounted on short shafts. The brush-shafts rotate in said brush-bearings and pass therethrough and at their outer ends are provided with intermeshing gears B^{24} , rotative motion being transmitted to the series of gears by a pinion B^{25} , fast on a shaft B^{26} , having end bearings in the bracket B^{27} and in the end wall H^X , the said shaft having a gear B^{28} thereon (see dotted lines, Fig. 10) in mesh with a gear B^{29} on the shaft of the brush B^{22} . The gear B^{28} is in turn in mesh with the large ring-gear 90, by which it is rotated.

It has been said that the transferrers by the number of rotations they make determine the number of nails which are to be taken from each raceway and discharged into the pockets of the receiver, and the mechanism for controlling or determining the number of nails to be transferred now remains to be described.

The shaft r^5 , which rotates the transferrers R^X , passes through the end H^3 of the auxiliary hopper and has an end bearing in the bracket H^{16} , said shaft having at its outer end a long pinion r^{10} , which is adapted to be engaged by any one of a series of gears of different diameters 301 302 303 304, (see Figs. 5, 5^a, 5^b, 6, and 8,) the gear 301 being the largest and when in mesh with the pinion R^{10} causing the transferrers to be rotated the greatest number of times—in this instance five—while the other three gears cause, respectively, four, three, and two rotations of the

transferrers. These several gears are mounted on like bell-crank levers 310, 320, 330, and 340, (see Fig. 5^b), loosely journaled on a short shaft 500, having its bearings in a boss 501 on the hopper end H³ and on an extension M⁷ of the frame M^X. The free end of each of said gear-carriers is provided (see Fig. 5^a) with two recesses 288-289, one or other of which is adapted to be entered by the inner 5 end of a locking-stud, shown as the reduced end of a screw 290, mounted in a horizontally-extended arm M⁶, fast on the hopper end H³. When the locking-stud is in the lower recess, as 289, (see Fig. 5^a), the gear supported on 10 that carrier—in this instance the gear 304—will be held in mesh with the pinion r¹⁰. The four gears 301, 302, 303, and 304 are in mesh, respectively, with gears 31, 32, 33, and 34, interposed between the carriers and fast on 15 the shaft 500, each of the latter four gears being always in mesh with its corresponding gear mounted on the locking-carriers. The shaft 500 has loose thereon a clutch member 502, provided with a worm-gear 503, in 20 mesh with the worm n on the auxiliary shaft N, and a coöperating clutch member 504 is splined on the shaft and normally pressed toward the loose clutch member by a suitable spring 505. The clutch member 504 has, as 25 best shown in Fig. 8, an edge cam 506 thereon, which terminates at one end in a shoulder or stop 507, (see dotted lines, Fig. 8, and full lines, Fig. 5^b), to be engaged at times by a detent n²⁵, shown as a rod mounted to slide 30 in a suitable bearing n²⁶ and connected at its lower end to one end of a lever n²⁷, pivoted on the under side of the frame M^X, the other end of the lever n²⁷ being acted upon by the upper end of a link n²⁸, vertically movable in 35 a bearing n²⁹ on the main frame of the machine and connected at its lower end to the treadle B⁵. (See Fig. 2.) When the treadle is depressed, the link n²⁸ is elevated to withdraw the detent n²⁵ from the clutch member, 40 which is immediately by its spring thrown into engagement with the coöperating member 502, and the shaft 500 is rotated to thereby transmit the desired rotation to the transferrers. It is to be noticed that this short 45 shaft 500 is only rotated once for each operation of the machine, for the stop 507 on the clutch member will be engaged by the detent n²⁵ at the completion of such revolution, the cam 506 separating the two clutch members. 50 Inasmuch as the end of the lever n²⁷ merely rests upon the upper end of the link n²⁸, it presents no obstacle to the movement of the nail-separating mechanism as a whole when 55 it is desired to swing it to one side on its turn-table. The shaft 500 has, as best shown in Fig. 5^b, a cam 510 fast thereon, the hub of the cam extending into the boss 501, forming a bearing for the shaft, said cam (shown in side elevation in dotted lines in Fig. 7) coöperating 60 with a depending arm t²⁰, fast on the rock-shaft t⁸, the cam having a notch 512 in its periphery, one side of said notch being substan-

tially radial and the other side, as 513, gradually rising to the circular periphery. The rotation of the shaft 500 in the direction of the arrow 66, Fig. 7, acts to move the nail-receivers and the detaining-ledges S⁶ into operative position while the nails are being moved into position by the transferrers, and when the notch in the cam arrives opposite the end of the arm t²⁰ the latter is moved toward the center of the cam suddenly by virtue of the spring T⁸, and the parts are thus restored to the position shown in Fig. 7.

While I have herein shown one embodiment of my invention, the same is not restricted to the precise construction, arrangement, and operation of parts as herein shown, for the construction and arrangement may be varied in numerous particulars without departing from the spirit and scope of my invention.

It will be obvious that the nail-separating mechanism herein shown may be applied to other forms of nailing mechanism, and my invention is not restricted to the use of a main and an auxiliary hopper.

Having fully described my invention, what I claim as new, and desire to secure by Letters Patent, is—

1. In an apparatus of the class described, a heel-support; a shoe-holder; mechanism to effect a continuous relative movement of said parts and impart a predetermined fixed pressure to the heel and shoe, actuating means for said mechanism, having a definite and constant movement, and means controlled by the height and density of the heel to be compressed to automatically render said mechanism inactive after said fixed pressure has been attained, and while the actuating means completes its movement, whereby heels of different heights and density will be subjected to the same pressure, substantially as described.

2. In an apparatus of the class described, a heel-support; a shoe-holder; mechanism to effect a continuous relative movement of said parts and impart a predetermined fixed pressure to the heel and shoe, actuating means for said mechanism, having a definite and constant movement, and means controlled by the height and density of the heel to be compressed to automatically render said mechanism inactive after said fixed pressure has been attained, and while the actuating means completes its movement, whereby heels of different heights and density will be subjected to the same pressure, combined with nail-driving devices to drive nails into the heel while the latter is subjected to pressure, substantially as described.

3. In an apparatus of the class described, a heel-support; a shoe-holder; means to effect a relative movement of said parts and impart a predetermined fixed pressure to the heel and shoe, said means including a cam-carrier, and a cam thereon having a limited movement relative to the carrier, and means to actuate the cam-carrier positively, the cam

moving with the carrier until the point of predetermined pressure is attained and thereafter being held while the carrier completes its movement, substantially as described.

5 4. In an apparatus of the class described, a heel-support; a shoe-holder; means to effect a relative movement of said parts and impart a predetermined fixed pressure to the heel and shoe, said means including a longitudinally-movable plunger, and a cam to move it, combined with cam-actuating mechanism having a definite movement, means to move said mechanism positively for a constant distance, and a friction-controlled connection between 10 the cam and its said actuating mechanism, whereby the cam will be automatically held from further movement when a predetermined fixed pressure upon the heel has been effected, while the cam-actuating mechanism 15 completes its movement, substantially as described.

5 5. In an apparatus of the class described, a heel-support; a shoe-holder; means to effect a relative movement of said parts and impart a predetermined fixed pressure to the heel and shoe, said means including a rotatable cam-carrier, a cam frictionally connected therewith and having a limited movement relative to the cam, combined with means to positively 20 rotate the cam-carrier for a constant distance, the cam moving with the carrier until the pressure upon the heel overcomes the friction between said cam and carrier, substantially as described.

35 6. In an apparatus of the class described, a heel-support; a shoe-holder; means to effect a relative movement of said parts and impart a predetermined fixed pressure to the heel and shoe, said means including a cam-carrier, and a cam thereon having a limited movement relative to the carrier, means to actuate the cam-carrier positively, the cam moving therewith until the pressure upon the heel stops the movement of the cam, and a device to 50 turn the cam to normal position on its carrier during the reverse movement of the latter, substantially as described.

7. In a heel-nailing machine, a heel-support; a spanker-plate at each side thereof; two shoe-holders, a laterally-movable carriage in which said holders are vertically movable independently, and means to move the carriage laterally, combined with a series of reciprocating plungers located below said spanker-5 plates and heel-support respectively and beneath the path of movement of the carriage, whereby the shoe-holders may be moved into position to be acted upon simultaneously by two of said plungers, to nail a heel on one 10 and spank a heel on the other of said holders, the latter being moved alternately into position below the heel-support, substantially as described.

8. In a machine of the class described, a shoe-holder; a coöperating positioning device for the shoe, comprising a support, upturned separable arms mounted to slide lat-

erally thereon, an equalizing connection between said arms, clamping members pivotally mounted on said arms, to grasp the sides of 70 the shoe, and connections between said members and the equalizing connection for the arms, whereby movement of the clamping members automatically effects corresponding movement of the arms, substantially as described. 75

9. In a machine of the class described, a shoe-holder; a coöperating positioning device for the shoe, comprising a support, upturned separable arms mounted to slide laterally 80 thereon, and provided with opposed racks, a pinion in engagement therewith, a pinion-shaft rotatably mounted in the support, clamping members for the shoe, pivoted to swing laterally on said arms, and links eccentrically connected with said shaft and jointed to the clamping members, whereby swinging movement of the latter will rotate the pinion-shaft to move the arms, substantially as described. 85

10. In a machine of the class described, a vertically and laterally movable work-holder, a coöperating positioning device for the shoe held thereon, comprising a vertically and laterally movable support mounted on the main frame, upturned separable arms adapted to slide on said support, clamping members pivoted on the arms to grasp the sides of the shoe, means between said arms and members, whereby movement of the latter effects movement of the former, and a connection between the work-holder and positioning device, whereby they will be moved in unison, substantially as described. 95

11. In a machine of the class described, a work-holder, a coöperating positioning device for the shoe mounted on the holder, said device and holder being independently supported on the main frame and each having a vertical and lateral movement, and a connection between said holder and positioning device, whereby they will be moved in unison, substantially as described. 105

12. A nail-block comprising a plurality of superposed sections having registering series 115 of nail-driving passages therein, the top section being cut away at the upper ends of the driving-passages therein, to permit the use of a decreased length of driver, and delivery-throats in said top section leading to the 120 driving-passages and having their outer ends located above the said cut-away portion, substantially as described.

13. In a heel-nailing machine, a removable nail-block having nail-driving passages therein, delivery-throats leading to said passages, a series of nail-transmitting tubes connected at their lower ends with said throats, and a support for the upper ends of said tubes, mounted on and movable with the nail-block, 125 combined with nail-separating mechanism adapted to be swung bodily to one side, and distributing-tubes leading therefrom and adapted to register at their lower ends with 130

the upper ends of the said transmitting-tubes, to distribute nails thereto when the separating mechanism is in operative position, substantially as described.

5 14. In a heel-nailing machine, a stationary nail-block; nail-separating mechanism adapted to be swung bodily to one side; and stationary nail-distributing tubes mounted on the nail-block to deliver nails to the nail-block when the separating mechanism is in operative position, substantially as described.

15 15. In a heel-nailing machine, nail-driving mechanism; nail-separating mechanism adapted to be swung bodily out of operative position, and stationary connections between said driving and separating mechanisms, to deliver nails to the former to be driven while the separating mechanism is in operative position, substantially as described.

20 16. Nail-separating mechanism, a support therefor upon which it is pivotally mounted and adapted to be swung out of operative position, and an actuating-shaft for said mechanism, concentric with the pivot thereof and mounted in the said support, substantially as described.

25 17. Nail-separating mechanism, a support therefor upon which it is mounted and adapted to be swung laterally into inoperative position and also to be tipped, an actuating-shaft mounted in the said support and concentric with the upright fulcrum of said mechanism, an auxiliary shaft carried by the said mechanism, and a universal connection between said actuating and auxiliary shafts, substantially as described.

30 18. Nail-separating mechanism, a support therefor upon which it is pivotally mounted and adapted to be swung out of operative position, a track on the support, to sustain the said mechanism when swung to one side, and an actuating-shaft for the separating mechanism, mounted in said support concentric with the pivot of said mechanism, substantially as described.

35 19. Nail-separating mechanism, a turn-table upon which it is pivotally mounted to be tipped, a support for and upon which said turn-table has its bearing, and means to actuate the separating mechanism when in operative position, substantially as described.

40 20. In a nail-separating mechanism, a hopper to receive nails in bulk, and rotatable nail-lifting devices consisting of a series of 45 open pockets of different depths and having their inner walls at different angles, to take nails from the lower portion of the hopper and discharge them at different points across the width of the hopper, substantially as described.

45 21. In a nail-separating mechanism, a hopper to receive nails in bulk, and rotatable nail-lifting devices including a series of open pockets to take nails from the bottom of the hopper, and having their mouths constructed to discharge the nails at different points across

the width of the hopper, substantially as described.

5 22. In a nail-separating mechanism, a hopper to receive nails in bulk, and comprising 7 fixed ends and a rotatable body portion, and nail-lifting pockets on the inner surface of the body, to take nails from the bottom of the hopper, the mouths of the pockets being constructed to discharge the nails at different 7 points along the path of the body portion, substantially as described.

15 23. In a nail-separating mechanism, a double-compartment hopper, comprising 8 fixed outer ends and a common intermediate wall, and rotatable body portions, nail-lifting devices for each compartment, whereby nails of different lengths may be separated, and a nail-raceway for each compartment, one raceway being open in one compartment and having a closed portion extended through the other compartment, to prevent entrance of nails from the latter to said raceway, substantially as described.

20 24. In a nail-separating mechanism, a hopper to receive nails in bulk, and comprising 9 fixed ends, and a rotatable body portion having a normally-closed opening for insertion or withdrawal of the nails, and nail-lifting devices on the body portion, combined with an actuating-shaft, connections between it and the body portion, to rotate the latter, and means to disconnect said shaft, whereby the body portion may be reversely rotated by hand to quickly empty the nail-lifting devices, substantially as described.

25 25. In a nail-separating mechanism, a hopper to receive nails in bulk, an inclined raceway therein which supports the nails by their heads with their bodies depending below it, devices to lift the nails from the hopper to the raceway, a detent located below the raceway, to engage the body of and hold the endmost nail of the series in the raceway and maintain the nails upright, a coöperating rotatable pick-off to engage said endmost nail just below its head and take it from the raceway, and independent means to separate such nail from the series of nails while they are held in upright position and as the pick-off moves into operative position, substantially as described.

30 26. In a nail-separating mechanism, a raceway composed of two slightly-separated parallel, oppositely-rotated rolls, to support the nails by the heads thereof with their bodies depending, a pick-off rotatable at the end of and concentric with one of said rolls, to take the endmost nail from the raceway, and means to hold the endmost nail of the series and to separate it from the next adjacent nail as the pick-off moves into operative position, substantially as described.

35 27. In a nail-separating mechanism, a raceway to support a series of nails with their bodies depending, means to separate the nails one by one at the delivery end of the race-

way, a nail-receiver, a transerrer to transfer one or more nails from said raceway to the receiver, and controlling means for said transerrer, whereby one nail or a plurality 5 of nails will be transferred, substantially as described.

28. In a nail-separating mechanism, a raceway to support a series of nails, means to separate the nails one by one at the delivery 10 end thereof, a receiver from which the nails are distributed, an intermittently-movable transerrer to transfer one or more nails from the raceway to the receiver, controlling means for said transerrer, to govern the number of 15 nails to be transferred, and a retaining device to prevent discharge of the nail or nails from the transerrer until its operative movement has been completed, substantially as described.

29. In a nail-separating mechanism, a nail-raceway, a receiver from which the nails are distributed, an intermittently-movable transerrer intermediate the raceway and receiver, nails being taken singly from the raceway and 25 accumulated by the transerrer, and means to govern the movement of the transerrer and thereby determine the number of nails to be accumulated thereby prior to delivery to the receiver, substantially as described.

30. In a nail-separating mechanism, a nail-raceway, a rotatable transerrer provided with a pick-off, to take a nail from the raceway at each rotation of the transerrer, means to effect one or more rotations of the transerrer, 5 to determine the number of nails to be transferred, and a receiver for the nails so transferred, substantially as described.

31. In a nail-separating mechanism, a nail-raceway, a rotatable spiral transerrer to receive nails singly therefrom, a retaining device coöperating with the transerrer, to form a stationary support along which the nails are moved by rotation of said transerrer, and 5 means to withdraw the retaining device and thereby release the nails, substantially as described.

32. In a nail-separating mechanism, a nail-raceway, a rotatable spiral transerrer to receive nails singly therefrom, a retaining device coöperating with the transerrer, to form a stationary support along which the nails are moved by rotation of said transerrer, a nail-receiver located beneath the transerrer and having a series of nail-pockets normally 5 open at one side, and means to move said receiver against the retaining device to close the pockets and also to move said device to release the nails from the transerrer, substantially as described.

33. In a nail-separating mechanism, a hop-

per for the nails in bulk, means to deliver separated nails therefrom at different points, and means to determine at will whether one nail or a plurality of nails shall be delivered at each of such points, substantially as described. 65

34. In a nail-separating mechanism, a hopper for nails in bulk, a plurality of raceways therein, lifting devices within the hopper, to lift nails and drop them on the several raceways, means to take the nails from each of 70 said raceways, and means to determine at will whether one nail or a plurality of nails shall be delivered from each raceway, substantially as described.

35. In a nail-separating mechanism, a main 75 and an auxiliary hopper, placed end to end, a nail-raceway for each hopper, one of said raceways extending from the auxiliary hopper through the main hopper, a guard to prevent entrance of nails from the main hopper 80 to the raceway leading from the auxiliary hopper, a common distributing device for the nails, and means to transfer nails from said raceways to said device, whereby nails of different lengths may be distributed, substantially as described. 85

36. In a nail-separating mechanism, a raceway composed of two parallel and oppositely-rotated separated rolls, to support the nails by the heads thereof with their bodies depending, end-thrust ball-bearings for one of said rolls, a transerrer in axial alinement with the other roll, and separated therefrom by a series of antifriction-balls, end-thrust ball-bearings for the opposite ends of said roll 95 and transerrer, and means to rotate them, substantially as described.

37. In a nail-separating mechanism, a hopper having a rotatable body portion and fixed ends, nail-raceways extended therethrough 100 and each consisting of a pair of slightly-separated oppositely-rotated rolls, a slotted guide-plate through which the lower ends of the rolls extend, two parallel separated bearing-plates extended transversely across the 105 lower ends of the raceways, ball-bearings in one of said plates for the longer roll of each raceway, a spirally-grooved transerrer in alinement with and separated from the end of the shorter roll by antifriction-balls, and 110 end-thrust ball-bearings in the second bearing-plate for the outer ends of the transmitters, substantially as described.

In testimony whereof I have signed my name to this specification in the presence of 115 two subscribing witnesses.

HENRY W. WINTER.
